UNITED STATES PATENT OFFICE.

RAYMOND SMITH, OF NEW YORK, N. Y., ASSIGNOR TO BELLA SMITH, OF NEW YORK, N. Y.

HAT.

Application filed October 2, 1923. Serial No. 666,063.

To all whom it may concern:

Be it known that I, RAYMOND SMITH, a citizen of the United States, residing in the borough of Manhattan of the city of New

5 York, in the State of New York, have invented certain new and useful Improvements in Hats, of which the following is a specification, reference being had to the accompanying drawings, forming a part hereof.

This invention relates to hats and is concerned particularly with the type of hat known as a tam-o'shanter or sailor in which a stiff head band carries a soft crown portion. The principal object of the invention is to provide a hat of this character which shall be provided with an adjustable head band of simple and inexpensive construction but by means of which, through simple manipulation, the band may be expanded or contracted and fastened in adjusted position to adapt itself to the particular size of the head of the wearer. Proposals of this same general nature have been made heretofore and no claim will be made hereinafter broadly to the provision of an adjustable head band apart from the particular means shown and described herein and as applied to hats of the particular type defined above. 15 In accordance with the invention it is proposed that the head band shall be made up in the conventional manner except that provision shall be made for telescoping the ends of the band so that while one end slides into a pocket formed in the lining for the band the overlapping end which is exposed to view shall form a slightly and unbroken continuation of the band and be provided with fastening devices to facilitate its permanent adjustment. It is proposed, further, in the interest of sightlessness to so attach the band to the crown that the free overlapping end thereof shall come at a point below a side seam in the crown which itself may be opened for a short distance above the band to adapt the crown to the telescoping adjustment without bulging.

These and other features will appear with greater particularity hereinafter in connection with the detailed description embodied herein, wherein:

Figure 1 is a view in perspective of a tam-o'shanter or sailor hat embodying the improvements.

Figure 2 is a fragmentary detailed view

in section through the band taken on the plane indicated by the line 2—2 of Figure 1 and looking in the direction of the arrows and showing the relation of the telescoping ends.

Figure 3 is a fragmentary view in side elevation showing a different form of securing devices for the overlapping end of the band.

Figure 4 is a view similar generally to Figure 3 but showing still another form of securing device.

The type of hat with which the invention is concerned comprises generally a soft crown *a* and a stiff head band *b* secured thereto. In accordance with the improvements this head band is formed as an open-ended strip and the lining *c* for the band is formed with a pocket to receive one end *b'* of the band in telescoping engagement while the other free end *b''* of the band overlies the end *b'* and is exposed to view. This last named free end *b''* may, if desired, be tapered or otherwise formed to give it a slightly appearance and facilitate its insertion through a loop *d* stitched to the band *b*. At the point where the crown *a* is stitched to the overlapping ends *b'*, *b''*, of the band *b* there is provided a seam *e* which is left open for an appreciable distance above the band *b* as indicated at *e'* so as to facilitate relative movement between the ends *b'*, *b''*, without causing bulging of the crown portion at this point. The material of the crown *a* may itself overlap along the open seam *e'* and readily follow the movements of the respective ends *b'*, *b''*, to which it is secured without any interference. The free end of the overlapping portion *b''* of the band is fastened to the band *b* by any convenient fastening devices, three types of which are shown in the drawings. In the form shown in Figures 1 and 2 a hook *f* is sewed to the inner side of the overlying end *b''* near its end and is adapted to engage any one or number of eyes *g* sewn onto the band *b* at such points as would give an adjustment to typical heads within limits.

In Figure 3 there is shown a stud *h* on the overlying flap *i* which may be engaged with any one of a series of sockets *k* as will be understood to effect the desired adjustment to size.

In Figure 4 a strap *l* is shown as stitched to the end of the overlying flap *m* and en-

gageable with a retaining buckle *n* secured on the head band as is clear.

The construction proposed is characterized by the utmost simplicity and inexpensiveness in manufacture since practically no departure is made from the conventional method now followed except that the hat band is made of such length as to enable its ends to overlie to the desired degree necessary for effecting the proper adjustments within limits through the telescoping action described. The smooth contour of the band is wholly retained for the comfort of the wearer and its external appearance is preserved in pleasing form.

What I claim is:

In a hat having a stiff head band and a lining therefor, open ends formed in the band, a pocket in the lining to receive one

of said ends in telescoping engagement, the other end being adapted to overlie the outer surface of the band, a loop on the band through which the last named end passes, a fastener secured on the inner side of the last named end, co-operating fastening means sewed to the outer surface of the head band at a point beyond the loop for engagement selectively by said fastening device on the end for regulation of the size of the head band, and a seam in the crown open for an appreciable distance above the head band in proximity to the overlying ends, the sides of said seam being disposed in overlapping relation.

This specification signed this 29th day of Sept. A. D. 1923.

RAYMOND SMITH,
